GOLF BALL

Thomas W. Miller, Ashland, Ohio, assignor to
 The Worthington Ball Company, Elyria, Ohio,
 a corporation of Ohio

Application July 17, 1930. Serial No. 468,530

16 Claims. (Cl. 273—62)

My invention relates to golf balls and to processes for making golf balls.

One of the objects of this invention is to provide a golf ball of improved construction and 5 having improved playing qualities.

Another object of my invention is to provide a golf ball admitting of uniform production in quantities.

Another object of my invention is to provide, 10 in a golf ball of the type having a liquid or semi-liquid filled core, in which the filling material is contained in a spherical shell, an improved construction for the shell.

Other objects will be apparent to those skilled 15 in the art to which my invention pertains.

My invention is fully described in the following description, taken in connection with the accompanying drawing:—

Fig. 1 is a cross-sectional view of a golf ball 20 embodying my invention with a center or core thereof in elevation.

Fig. 2 is a view showing the two shell-like sections from which a spherical core shell, which I employ, is constructed.

Fig. 3 is a plan view taken from above of one 25 of the core shell sections shown in Fig. 2.

Fig. 4 is a cross-sectional view of the completed core shell.

Fig. 5 is a view of a fragment of a vulcanizing 30 mold, showing the two shell sections positioned therein for molding by their rim flanges.

Fig. 6 is a view of my invention showing part 35 of a cap, which may be employed for the filled core shell, in section.

The completed golf ball of my invention, illustrated in Fig. 1, comprises a central core or ball center 1, which will be described in more detail later. Around the core is wrapped a layer of 40 rubber threads or bands 2, stretched to produce constricting tension, the wrapping being carried on to produce a layer of suitable thickness around and enclosing the core 1.

Finally, a balata rubber covering 3 is molded on and around the layer of rubber threads 2, this 45 covering preferably being made by first forming two semi-spherical shells of the material thereof and then enclosing the core 1 and wrapped layer 2 within the shells, and then joining the shells at their annular edges by heating and pressure. Any fin or other irregularity occurring at the 50 joint or union of the semi-spherical shells is thereafter removed in any suitable manner. The center or core 1 will now be described.

The core 1 is of the type comprising an outer 55 casing or shell and a filling of plastic, liquid, or

semi-liquid material therein. I am aware that cores of this general class have been employed heretofore, but the construction thereof has produced cores which have been out-of-round, and out of balance, with the resulting detriment 60 to the playing qualities of the finished ball.

The core of the golf ball of my invention comprises a spherical shell of thin, soft, resilient rubber, so constructed as to be truly spherical to a relatively high degree of accuracy, and completely filled with a plastic, liquid, or semi-liquid material; and thus when employed as the core of a golf ball, it provides a ball the material of which is disposed symmetrically around its center and symmetrically balanced, upon which 65 qualities, as is well known, depend the playing 70 quality of the golf ball.

In constructing the spherical core shell I first provide a pair of substantially semi-spherical shells 4 and 5, as shown in Fig. 2, molding them 75 from thin, soft rubber. The upper of the two shells 5, as they appear in the drawing, Fig. 2, may be provided with spaced perforations 6 and 7 in the wall thereof symmetrically disposed with respect to the axis of symmetry of the semi-spherical shell, as described in application for 80 United States Letters Patent, Serial No. 405,508, filed November 7, 1929, by Willis E. Reichard.

The shell 5 is also provided with a circular line 8 inscribed or molded in the exterior surface of 85 the shell and having its center on the said axis of symmetry, and being disposed in a plane at right angles thereto, the purpose of which will be described.

The annular edges of the shells 4 and 5 are 90 formed with inwardly directed annular flanges 30 and 31 respectively outwardly formed to planar faces 32 and 33 respectively, in the plane of the edges. The two semi-spherical shells 4 and 5 thus provided are next joined along the 95 planes 32 and 33 of the flanges 30 and 31, by cementing or vulcanizing or any other well-known method, and thus producing a complete spherical core shell 9, as shown in Fig. 4.

By means of the flanges 30—31 and their 100 planar faces 32—33 a very strong joint between the semi-spherical shells may be had. The semi-spherical walls of the shells may be relatively thin, but the flanges 30—31 providing large annular joining areas.

The core shell thus produced is next filled with either a plastic, liquid, or semi-liquid filling material and sealed by any approved process such as a cap 28, as shown in Fig. 6, described in application for United States Letters Patent, Serial 110

No. 405,508, filed November 7, 1929, by Willis E. Reichard.

Preferably the shell wall is formed thinner at that portion containing the perforations as shown in drawing Figs. 2 and 4 by depressing the external surface. Thus, after the cap 28 is applied, the wall of the entire completed shell may be of uniform thickness, the thickness of the material of the cap supplementing the thin wall portions; 10 and, thus, the completed core may be a perfect sphere externally as shown in Figs. 1 and 6. In this connection the cap 28 may be a disc in the form of a sphere section and with a very thin annular edge as shown in Fig. 6 and the thin wall 15 portion of the shell may be formed to a supplemental variable thickness to produce a uniform wall thickness as described. The material of the shell is, thus, symmetrically balanced around the sphere center whereby a perfectly balanced and 20 symmetrical ball core and finished golf ball including such core is rendered possible. It is obvious that the relatively heavy annular flanges 30 and 31 are in balance around the center.

The ball core 1 or center, is now complete, the 25 filling material completely filling the spherical shell and the material of the core is now substantially symmetrically disposed around the center thereof, producing a spherical and balanced core.

When the completed core 1 has been embodied 30 in the golf ball as hereinbefore referred to in connection with the description of Fig. 1, a complete golf ball having a plastic, liquid, or semi-liquid core is provided, all the parts of which are either spherical, as for instance the filling material of the core, or lie in spherical lines symmetrically disposed around the center of the ball, and thus the ball with a plastic, liquid, or semi-liquid core type is provided with superior claim 35 qualities.

40 My invention is not limited to the exact details of construction shown and described, inasmuch as many changes in and modifications thereof may be made within the scope of my invention, but without departing from the spirit thereof or 45 sacrificing its advantages.

As will now be clear, one of the advantages of my invention is that it permits the employment of a filling material of any degree of fluidity, from very thin free flowing materials to semi-liquid 50 viscous, or even plastic materials, and therefore my invention is in no sense limited to any particular filling material or degree of fluidity thereof.

In the claims, the term fluid will be understood to apply to all such materials.

55 I claim:

1. A casing for the fluid material of a golf ball of the fluid core type, constructed from a pair of substantially hemispherical shells of rubber or like material, joined together at their annular edges, and a portion of the external spherical surface of one shell being flattened relative to its adjacent inner surface to provide a relatively thin wall portion, and a pair of spaced perforations in the said wall portion, through one of which filling 60 material may be injected and out of the other of which air may escape.

2. A casing for the fluid material of a golf ball of the fluid core type, constructed from a pair of substantially hemispherical shells of resilient 70 rubber or like material, joined together at their annular edges and a portion of the external spherical surface of the casing wall being flattened relative to its adjacent inner surface to provide a relatively thin wall portion, and a pair of 75 spaced perforations in the said wall portion,

through one of which filling material may be injected and out of the other of which air may escape.

3. A center for golf balls comprising a hollow spherical shell of rubber or like resilient material 80 the wall thereof being of generally uniform thickness and a portion of the external spherical surface being flattened to provide a relatively thin wall portion, a pair of spaced perforations in said wall portion, through one of which filling material may be injected and out of the other of which air may escape, a fluid material filling the shell and a cap sealed upon the shell at said thin portion and covering and sealing the perforations. 85

4. A center for golf balls comprising a hollow spherical shell of rubber or like resilient material, the wall thereof being of generally uniform thickness and a portion of the external spherical surface thereof being flattened to provide a relatively thin wall portion, a pair of spaced perforations in said wall portion, through one of which filling material may be injected and out of the other of which air may escape, a fluid material filling the shell, and a cap sealed upon the shell at said thin portion and covering and sealing the perforations and the combined thickness of the thin portion and of the cap thereon being substantially the same as the thickness of the other portions of the shell wall. 90

5. A center for golf balls comprising a hollow spherical shell or like resilient material, the wall thereof being of generally uniform thickness and a portion of the external spherical surface thereof being flattened to provide a relatively thin wall portion, a pair of spaced perforations in said wall portion, through one of which filling material may be injected and out of the other of which air may escape, a fluid material filling the shell and a cap sealed upon the shell at said thin portion and covering and sealing the perforations, said shell being formed from a pair of substantially hemispherical shell portions joined together at their annular edges. 100

6. A center for golf balls comprising a hollow spherical shell of rubber or like resilient material, the wall thereof being of generally uniform thickness and a portion of the external spherical surface thereof being flattened to provide a relatively thin wall portion, a pair of spaced perforations in said wall portion, through one of which filling material may be injected and out of the other of which air may escape, a fluid material filling the shell and a cap sealed upon the shell at said thin portion and covering and sealing the perforations 110 said shell being formed from a pair of substantially hemispherical shell portions joined together at their annular edges, and the said wall portion and perforations being formed in one of the shell portions. 120

7. A center for golf balls comprising a hollow spherical shell of rubber or like resilient material, the wall thereof being of generally uniform thickness and a portion of the external spherical surface thereof being flattened to provide a relatively thin wall portion, a pair of spaced perforations in said wall portion, through one of which filling material may be injected and out of the other of which air may escape, a fluid material filling the shell and a cap sealed upon the shell 130 at said thin portion and covering and sealing the perforations, the combined thickness of the thin portion and of the cap thereon being substantially the same as the thickness of the other portions of the shell wall, said shell being formed from a 140

- pair of substantially hemispherical shell portions joined together at their annular edges, and the said wall portion and perforations being formed in one of the shell portions. 80
- 5 8. In a casing for golf ball cores of the fluid core type, a substantially hemispherical shell of rubber or like material, a portion of the shell wall being externally flattened to provide a relatively thin wall portion and a pair of spaced perforations in said portion. 85
- 10 9. A center for golf balls comprising a hollow spherical shell of rubber or like resilient material, the major portion of the wall thereof being of generally uniform thickness and a portion of the external spherical surface thereof being flattened to provide a relatively thin wall portion, a perforation in said wall portion through which filling material may be injected, a fluid material filling the shell, and the wall comprising a cap upon the shell at said thin portion covering and sealing the perforation and increasing the wall thickness at the thin portion to substantially the same thickness as that of the major portion. 90
- 15 10. A center for golf balls comprising a hollow spherical shell constructed from a pair of substantially hemispherical shells of resilient rubber or like material and of generally uniform wall thickness joined together at their annular edges and a portion of the external spherical surface of the shell being flattened to provide a relatively thin wall portion, a perforation in said wall portion through which filling material may be injected, a fluid material filling the shell, and the wall comprising a cap upon the shell at said thin portion covering and sealing the perforation and increasing the wall thickness at the thin portion to substantially the same thickness as that of the remainder of the said shell. 95
- 20 11. A casing for the fluid material of a golf ball of the fluid core type constructed from a pair of substantially spherical shells, of rubber or like material, joined together at their annular edges, and a portion of the casing wall being of reduced thickness, a pair of spaced perforations in said reduced wall portion through one of which filling material may be injected and out of the other of which air may escape. 100
- 25 12. A casing for the fluid material of a golf ball of the fluid core type constructed from a pair of substantially spherical shells, of rubber or like material, joined together at their annular edges, and a portion of the wall of one shell being of reduced thickness, a pair of spaced perforations in said reduced wall portion through one of which filling material may be injected and out of the other of which air may escape. 105
- 30 13. A center for golf balls comprising a hollow spherical shell of rubber or like resilient material, the wall thereof being of generally uniform thickness and a portion of the wall being of reduced thickness, a perforation in said reduced wall portion through which filling material may be adjusted, a fluid material filling the shell, and a cap sealed upon the shell at said reduced portion, covering and sealing the perforation, and the combined thickness of the reduced portion and of the cap thereon being substantially the same as the thickness of the other portions of the shell. 110
- 35 14. A center for golf balls comprising a hollow spherical shell of rubber or like resilient material constructed from a pair of substantially hemispherical shells having walls of substantially uniform thickness, a portion of the wall of one shell being of reduced thickness, a pair of spaced perforations in said reduced wall portion through one of which filling material may be injected and out of the other of which air may escape, a fluid material filling the shell, and a cap sealed upon the shell at said reduced portion, covering and sealing the perforations, and the combined thickness of the reduced portion and of the cap thereon being substantially the same as the thickness of the other portions of the shell. 115
- 40 15. A center for golf balls comprising a hollow spherical shell of rubber or like resilient material, the wall thereof being of generally uniform thickness and a portion of the wall being of reduced thickness, a perforation in said reduced wall portion through which filling material may be injected, a fluid material filling the shell, and a cap sealed upon the shell at said reduced portion, covering and sealing the perforation, and the combined thickness of the reduced portion and of the cap thereon being substantially the same as the thickness of the other portions of the shell. 120
- 45 16. A center for golf balls comprising a hollow spherical shell of rubber or like resilient material constructed from a pair of substantially hemispherical shells having walls of substantially uniform thickness, a portion of the wall of one shell being of reduced thickness, a perforation in said reduced wall portions through which filling material may be injected, a fluid material filling the shell, and a cap sealed upon the shell at said reduced portion, covering and sealing the perforation, and the combined thickness of the reduced portion and of the cap thereon being substantially the same as the thickness of the other portions of the shell. 125
- 50 17. A center for golf balls comprising a hollow spherical shell of rubber or like resilient material, the wall thereof being of generally uniform thickness and a portion of the wall being of reduced thickness, a perforation in said reduced wall portion through which filling material may be injected, a fluid material filling the shell, and a cap sealed upon the shell at said reduced portion, covering and sealing the perforation, and the combined thickness of the reduced portion and of the cap thereon being substantially the same as the thickness of the other portions of the shell. 130
- 55 18. A center for golf balls comprising a hollow spherical shell of rubber or like resilient material, the wall thereof being of generally uniform thickness and a portion of the wall being of reduced thickness, a perforation in said reduced wall portion through which filling material may be injected, a fluid material filling the shell, and a cap sealed upon the shell at said reduced portion, covering and sealing the perforation, and the combined thickness of the reduced portion and of the cap thereon being substantially the same as the thickness of the other portions of the shell. 135

THOMAS W. MILLER.
